BOX WALL FOR LOOMS

Filed Jan. 28, 1947

UNITED STATES PATENT OFFICE

2,594,170

BOX WALL FOR LOOMS

Harold Hoeber, deceased, late of South Dartmouth, Mass., by Barbara O. W. Hoeber and William T. Read, executors, Dartmouth, Mass., assignors, by mesne assignments, to Hoosac Mills Corporation, Boston, Mass., a corporation of Massachusetts

Application January 28, 1947, Serial No. 724,725

2 Claims. (Cl. 139—183)

1

This invention relates to a loom and more particularly to the wall of the shuttle box.

The shuttle box carried by the lay of a loom usually has a back wall which is attached at its inner end to the lay sword and may be adjusted at this end. The back wall in the Draper loom is cut out so that the back binder extends through this wall of the box and may swing inwardly. The outer portion of the back wall is fixedly mounted to the lay and at this outer end the back binder is pivoted. By this arrangement only the inner end of the back wall of the box may be adjusted and consequently the shuttle may be given a serpentine path by reason of the fact that the outer end of the back binder is not moved correspondingly when adjustment is made at the inner end of the back wall. Further, this back wall by reason of its cut out for the back binder is not rigid and may become distorted in its position. It forms an inadequate support for the back binder. If the binder were in the front wall the same would be true.

One of the objects of the invention is to provide a guiding surface for the shuttle above and below the binder so that the shuttle is subject to guidance, in its outward and inward motion, by a continuous rigid wall.

Another object of this invention is to provide a box wall which may be adjusted at the outer end of the shuttle box.

Another object of the invention is to strengthen the end of the lay.

Another object of this invention is to provide a better mounting for the box binder.

Another object of this invention is to provide a stronger and more rigid attachment for the lay end to the sword.

Another object of the invention is to provide a more rigid mounting for the hinge of the box binder.

Another object of the invention is to provide an improved means of attaching the box wall of the shuttle box to the lay.

Another object of the invention is to provide a means for vertically aligning guiding edges of the box wall of the shuttle box which mount the box binder.

With these and other objects in view, the invention consists of certain novel features of construction as will be more fully described and particularly pointed out in the appended claims.

In the accompanying drawings:

Fig. 1 is a sectional view illustrating a fragmental portion of a loom and illustrating more particularly the end of the lay showing the shuttle box;

2

Fig. 2 is a top plan view of the shuttle box with parts in section;

Fig. 3 is a sectional view on line 3—3 of Fig. 2;

Fig. 4 is a perspective view of the back of the shuttle box;

Fig. 5 is a section on substantially line 5—5 of Fig. 1.

In proceeding with this invention there is provided a rigid box wall for a shuttle box with a slot 10 therein, the wall being of sufficient thickness so that the slot will provide a surface area sufficient to provide a good support for the box binder which is pivotally mounted in this slot to work through the wall of the box. This box wall is 15 also mounted so that it will be adjustable at its outer end and also adjustable at its inner end.

Thus, the box wall may be nicely positioned to 20 locate the wall as desired that the shuttle may be guided in a straighter non-rotating path of travel when struck by the picker stick to drive it out of the box. By reason of the box wall providing 25 substantial masses on both sides of the binder, a very firm and solid pivotal mounting of the box binder is provided and the lay end is better reinforced.

With reference to the drawings, 10 designates a portion of the framework of the loom and 11 designates the lay swords which mount the lay 12 thereon. A reed 13 is carried by the lay carrying a cap 14. The protection rod is shown at 15 with an arm 16' extending upwardly therefrom to engage the box binder. The shuttle box is 20 designated generally 16 and as shown in Fig. 2 consists of a front wall 17, a bottom wall 18 (see Fig. 2) held in position by screws 19 and 20 with a front flange 21 and a back flange 22 or abutment extending downwardly on either side of the lay 12. A slot 23 is provided in the lay at the 25 location of the shuttle box for the reception of the picker stick 24 which is encircled by the check strap 25 carried by the check strap bracket 26 which is fastened onto the lay 12. The cushion member 27 is located at the outer end of this slot 23 and the picker 28 is mounted at the upper 30 end of the picker stick for engagement with the shuttle to throw it across the loom.

The back wall of this shuttle box 16 is designated generally 30 and is shown in perspective in Fig. 4. It is a rigid casting in one piece with 35 its widest portion 31 adapted to engage the upper end of the lay sword 11. Two abutment or filling strips 32 and 33 are provided for engagement with this lay sword while this portion 31 is drawn up against the lay sword by reason of a threaded opening 34 and a headed screw 35 (see Fig. 2) 40 which extends through the lay sword and into

this threaded opening 34. The position of this end of the back wall will be governed by the relative location of the surfaces of the abutments 32 and 33 which may be filed to provide the proper alignment while the bolt draws these securely against the surface of the lay sword. From the widest portion 31 the box back is narrower as at 36 and also thicker for greater support of the box binder. This portion is slotted as at 37 for the reception of the box binder 38 which slot 37 extends throughout the remainder of the length of the back wall and provides portions 39 and 40 in spaced relation which are connected by a bridging block 41 having a downwardly extending flange 42 provided with four threaded openings 43, 44, 45 and 46, these latter two openings 45 and 46 being vertically arranged with reference to each other.

This flange 42 is mounted on the lay by reason of screws 47 and 48 extending through the openings 43 and 44, and into threaded openings 49 and 50 in the flange 22 which extends downwardly from the bottom wall 18 of the shuttle box. These screws will draw this flange and consequently the inner end of the back wall inwardly as they are set up. Screws 51 and 52 (see Figs. 3 and 5) extend through the threaded openings 45 and 46 and are provided with check nuts 53 and 54 so as to hold these screws 51 in adjusted position. The inner end 55 of the screw 51 provides an abutment as does the inner end 56 of the screw 52 which engage the flange 22 and limit the amount that the outer end of the back wall 30 may be drawn inwardly by the screws 47, 48. By relatively setting up the screws 51 and 52 more or less the vertical alignment of the back wall 30 may be provided. By backing these screws out of their openings 45 and 46 and setting up the screws 47, 48 the outer end of the wall 30 may be drawn closer to the front wall, whereas if the screws 51 and 52 are set further inwardly through the threaded openings 45 and 46 and the screws 47 and 48 backed off further the outer end of the back wall will be positioned further away from the front wall of the shuttle box.

By this arrangement the back wall is positioned so as to closely guide the shuttle when projected from the box so as to further insure a straight flat throw. The arrangement of the upper and lower portions of the back wall is such as to prevent rotating of the shuttle about its longitudinal axis due to the action of the binder as the shuttle is picked out of the box.

The box binder 38 is provided with a hole adjacent the outer end of the shuttle box to align with holes 55' in the portion 39 and 56' in the portion 40 for the reception of a hinge pin 57

(see Fig. 2) which will extend through the aligned openings to hingedly mount the box binder 38 in the slot 37 in the back wall. This box binder will slide upon the inner surface 59 of the lower portion 40 of the box binder which provides a good supporting surface upon which it may rest. Due to the adjustment of the back wall the box binder will have little or no effect in guiding the shuttle. The box binder acts only as a frictional means and operates the protection system and, if desired, may be used as a subsidiary check for the shuttle and especially to hold the shuttle stationary momentarily when all the way home in the box.

What is claimed is:

1. A shuttle box for a loom lay having an abutment, said shuttle box comprising a front wall, a back wall formed of a single piece of rigid material and provided with a slot intermediate its upper and lower edges and spaced from one of its ends, a binder in said slot, means for mounting the outer end of said back wall for adjustment toward and from the front wall, said means comprising a threaded member threaded into said slotted wall and engaging said abutment.
2. A shuttle box as set forth in claim 1 wherein the second said means comprises a pair of vertically arranged threaded members threaded through said slotted wall and engaging said abutment for adjustment about the horizontal axis of said slotted wall.

BARBARA O. W. HOEBER,
WILLIAM T. READ,
Executors of the Estate of Harold Hoeber, Deceased.
